UNITED STATES PATENT OFFICE.

MAURUS C. RECK, OF ROCHESTER, NEW YORK, ASSIGNOR TO SILL STOVE WORKS, OF ROCHESTER, NEW YORK, A CORPORATION OF NEW YORK.

STOVE.

Application filed September 2, 1922. Serial No. 585,869.

To all whom it may concern:

Be it known that I, MAURUS C. RECK, of Rochester, in the county of Monroe and State of New York, have invented certain new and useful Improvements in Stoves; and I do hereby declare the following to be a full, clear, and exact description of the same, reference being had to the accompanying drawings, forming a part of this specification, and to the reference numerals marked thereon.

This invention relates to cooking stoves and more particularly to the variety provided with ovens for baking, roasting, broiling and the like, located at an elevation above the stove with an oven superstructure top and heated by gas or other suitable means, one object of the invention being to provide a stove of the above character having the superposed ovens efficiently and conveniently arranged to afford a maximum degree of accessibility for the attendant.

Another object is the provision of a stove of the above variety having the oven structure practically arranged to provide on its top a convenient warming shelf within easy reach of the attendant.

Still a further object is to provide a construction such as indicated above with the parts compactly and economically disposed to utilize a portion of the double insulating wall of one oven as a passageway for the escape of the products of combustion from the other oven to the main escape flue. To these and other ends the invention resides in certain improvements and combinations of parts all as will hereinafter be more fully described, the novel features being pointed out in the claims at the end of the specification.

In the drawings:

Figure 1 is a front elevation partly broken away of a cooking stove embodying the present invention;

Figure 2 is an enlarged elevation of the superstructure in section on a plane parallel with the stove front, and;

Figure 3 is an enlarged sectional side elevation of one of the ovens on the line 3^a—3^a of Figure 1.

Similar reference numerals throughout the several views indicate the same parts.

The invention is embodied in the present instance in combination with a cooking stove of an ordinary variety the main or lower

portion of which may comprise a coal burning structure or a combined coal and gas burning arrangement, together with a standard extending above the top of the stove at its back and carrying ovens heated by gas or other suitable means and adapted, for example, for broiling, baking, roasting and the like. The invention comprises, generally speaking, an advantageous arrangement and construction in combination with such a stove of a pair of ovens, one of relatively large size or height for baking, roasting and the like, and the other of relatively smaller size or height for broiling. It has been found that a pair of ovens differing in size and height, as consistent with the intended uses, may be advantageously arranged one beside the other with the lower oven adjacent the bottom of the higher oven within convenient reach of the attendant and with its top at a substantial distance from the top of the higher oven to afford a warming shelf for dishes and the like also brought by such arrangement within convenient reach of the attendant. This construction furthermore makes it possible to utilize a portion of the double outer wall of the higher oven adjacent and above the lower oven as a passageway for the escape of the products of combustion from the latter to the top of the higher oven and thence to the main escape flue, thus affording a compact and economical construction.

Referring more particularly to the drawings there is shown at 5, Figure 1, a stove in the present instance of the coal burning type having a top 6 on which is supported an upright or standard 7 for supporting the superposed ovens. The stove 5 may, of course, have other forms than that shown and the standard 7 may be constructed in any suitable manner, comprising in the present instance a back plate 8 with forwardly extending walls at its ends provided adjacent their tops with forwardly extending brackets 9 for supporting the ovens as well understood in the art.

The superposed ovens, of which in the present instance there are two, include a relatively large baking or roasting oven 10 at the left hand side of the stove having the usual front door 11. The bottom of this oven as shown is arranged at a substantial elevation above the top 6 of the stove so as not to interfere with the use of the latter

and is preferably constructed of sheet metal as best shown in Figure 2. As appears from this figure there is provided a gas burner 12 in the lower portion of the oven above which 5 is a baffle plate or false bottom 13 having upwardly extending sides 14 provided with tray holding brackets 15. The exterior sides of the oven preferably have the double wall construction indicated at 16, Figure 2, to 10 provide an intermediate insulating air space, as well understood in the art. Air inlet openings 17 are provided adjacent the bottom of the oven below the burner and the products of combustion, passing upwardly 15 through the spaces 18 and 19 between the inner oven walls 14 and the double exterior walls, are transmitted through openings 20 in an inner top plate 21 into a space 22 above the top of the oven. The latter communicates at its back with an escape connection 23, Figure 3, with the main escape flue or pipe 24.

The other or relatively small oven 25, adapted, for example, for broiling, is located 25 at the right hand side of the stove beside oven 10 and adjacent its bottom. That is to say, the bottoms 26 of the ovens are at the same level but the oven 25, being of less height than oven 10, has its top located at 30 a substantial distance below the top of oven 10, thus providing a warming shelf 37 within convenient reach of the attendant, while oven 25 is itself located as low as possible so as to be within easy reach. This oven also 35 is preferably constructed of sheet metal having in fact a bottom wall 26, Figure 2, preferably integral with that of the oven 10. Oven 25 is heated in the present instance by a gas burner 27 suitably supported adjacent 40 its top. It also has a baffle plate or false bottom 28 with upwardly extending inner side walls 29 provided with tray holding clips 30. The exterior side walls of oven 25 are also preferably double in construction, as indicated at 31, to provide suitable insulation and the front and rear walls of the oven have 45 a series of openings 32 and 33 respectively for the admission of air, the products of combustion passing out of the oven above the 50 burner through openings 34 in its inner top wall 35. Above wall 35 is a space 36 between the latter and an exterior top wall 37 into which the products of combustion pass. The 55 space is provided with an intermediate baffle plate 38 for deflecting the burned gases toward the left, Figure 2, at which side space 36 communicates with a space 39 which is formed by the double exterior wall of oven 10 somewhat enlarged at this portion. That 60 is to say, the double exterior wall of oven 10 here has the double function of serving also as an escape passage for the products of combustion from oven 25 and affording an exceedingly simple and economical joint construction for the two ovens.

The exterior top wall 37 of oven 25 forms an excellent warming shelf for dishes, being moderately heated from both ovens and the shelf has retaining walls formed by the outer side wall 40 of oven 10 and the back 70 plate 41 extending upwardly at the back of oven 25.

The double side wall of oven 10 thus affords an escape passage for the products of combustion from the lower oven 25 which 75 pass directly up and above the top plate of oven 10 and through the common discharge pipe 23 which may be controlled by any suitable damper means (not shown) if desirable. The products of combustion of one 80 oven therefore cannot enter the other. The relative arrangement and positions of the oven is not only advantageous by reason of the compact and economical form of construction pointed out, but also in the location of oven 25 at the lowest practicable elevation, so that it, as well as the warming shelf, are brought in convenient reach of the attendant.

I claim as my invention:

1. The combination with a cooking stove, of a standard extending upwardly thereabove, a baking oven carried by the standard at a substantial distance above the top of the stove, a broiling oven carried by the standard at one side and adjacent the bottom of said baking oven with its top located at a substantial distance below the top of said broiling oven to provide on the top of said broiling oven a warming shelf within easy reach of the attendant, and gas burner means for each of said ovens.

2. The combination with a cooking stove having a flue for the escape of the products of combustion, of a standard extending upwardly from the top of the stove, a relatively high gas heated oven carried by the standard at a substantial distance above the stove and having an escape connection adjacent its top with said flue, a relatively low gas heated oven carried by the standard beside said high oven with its bottom substantially level with the bottom of said high oven and its top at a substantial distance below the top of said high oven to provide on top of said low oven a warming shelf within convenient reach, gas burner means for each of said ovens, and an escape connection for said low oven extending up the adjacent side of said high oven into communication 115 at the top of the latter with said flue.

3. The combination of a cooking stove having a relatively high gas heated oven supported at a distance above the top thereof, an escape flue connected with the top of said high oven, a relatively low gas heated oven supported at one side of said high oven adjacent its bottom with its top at a substantial distance below the top 120 of said high oven to provide a warming 130

shelf within convenient reach, gas burner means for each of said ovens, and spaced side walls for said high oven at the portion thereof adjacent and above said low oven serving also as an escape connection between the top of the latter and the top of said high oven.

4. The combination of a cooking stove, a relatively high oven having double exterior side walls, means for supporting said oven at a distance above said stove, an escape flue connected with the top of said oven, a rela-

tively low oven carried by said supporting means at one side and adjacent the bottom of said relatively high oven with its top 15 at a substantial distance below the top of said relatively high oven to provide a relatively low warming shelf gas burner means for each of said ovens, and an escape connection between the top of said relatively 20 low oven and the top of said relatively high oven through the passageway enclosed by the adjacent double wall of the latter.

MAURUS C. RECK.
